UNITED STATES PATENT OFFICE.

VICTOR LABELLE, OF MONTREAL, QUEBEC, CANADA.

SOFA-BED.

No. 917,771.

Specification of Letters Patent.

Patented April 13, 1909.

Application filed April 20, 1908. Serial No. 428,244.

To all whom it may concern:

Be it known that I, VICTOR LABELLE, a subject of the King of Great Britain, residing at the city and district of Montreal, in the 5 Province of Quebec, Canada, have invented certain new and useful Improvements in Sofa-Beds; and I do hereby declare that the following is a full, clear, and exact description of the invention, such as will enable 10 others skilled in the art to which it appertains to make and use the same.

The present invention relates to combination furniture, and more particularly to that 15 class of furniture popularly known as sofa-beds.

Broadly speaking, it comprises two sections hinged together and adapted, in one position to form a bed, and in another position to form a sofa or lounge, and head rests 20 hinged to posts of the furniture and adapted to be turned out of the way when the furniture is to be used as a bed only.

In order to more clearly disclose the construction, operation and use of the invention, 25 reference should be had to the accompanying drawings forming part of the present application.

Throughout the several views of the drawings like reference characters designate the 30 same parts.

In the drawings: Figure 1 is a front view of the combination piece folded to form a sofa with the back rest in position; Fig. 2 is a similar view with the back rest removed and the 35 head-rests swung up to allow unfolding of the combination piece; Fig. 3 is an end view of Fig. 2; Fig. 4 is an end view showing the combination piece completely unfolded to form a bed; and, Fig. 5 is a plan view of Fig. 4.

Referring to the drawings in detail, 1 is a 40 lower boxlike frame in which is secured, either rigidly or removably, a series of slats or a slatted frame 2 upon which a mattress may be supported. To the rear edge of the 45 box frame 1 are fixed the end posts 3 and the stops 4. To the upward edge of the box frame 1 is hinged a second similar box frame 5 carrying a similar slatted frame 2 and adapted, through its hinged connection, to 50 fold back upon the first box frame 1, as shown in Fig. 3. At two corners of the frame 5 are placed pins 6. The pins 6 are adapted to fit into sockets 8 in the under edges of the swinging head-rests 9 which are 55 hinged to the upper ends of the posts 3, thus

holding the head-rests in position and preventing twisting of their hinges.

When the frames 1 and 5 have been folded together the head-rests are swung back into the position shown in Fig. 1 and the back 60 rest 11 is placed against the stops 4, the cushion 10 being placed between the stop strip 7 and the back rest. For supporting the frame 5, feet 12 are secured, either rigidly or pivotally, to the lower outer edge of the 65 same. Of course, when the furniture is used as a sofa these feet will be at the back of the same.

It is clear that many changes may be made in the construction of the several parts, 70 many rearrangements of these parts, and many other combinations of them, and many substitutions for them may be made without in any way departing from the field and scope of the invention and it is meant to 75 include all such within this application, wherein only a preferred form has been shown and described.

Having thus fully described my invention, what I claim as new and desire to secure by 80 Letters Patent is:

1. A combined sofa-bed of the character described, comprising two frames hinged together and adapted to be folded together in superposed position to form a sofa and unfolded to form a bed, posts secured to one of said frames and extending upward to a height equal to that of the two frames when folded together, head rests pivotally connected to the tops of said posts and adapted 85 to be swung rearwardly, stops secured to one of said frames, and a removable back rest adapted to be supported by said stops.

2. A combined sofa-bed of the character described, comprising two frames hinged together and adapted to be folded together in superposed position to form a sofa and unfolded to form a bed, posts secured to one of said frames and extending upward to a height equal to that of the two frames when 90 folded together, head rests pivotally connected to the tops of said posts and adapted to be swung rearwardly therefrom, stops secured to one of said frames, a removable back rest adapted to be supported by said stops, 95 and a stop strip secured to the other of said frames.

3. A combined sofa-bed of the character described, comprising two frames hinged together and adapted to be folded together in 100

superposed position to form a sofa and unfolded to form a bed, posts secured to one of said frames and extending upward to a height equal to that of the two frames when 5 folded together, head rests pivotally connected to the tops of said posts and adapted to be swung rearwardly therefrom and provided with sockets, and pins mounted on one of the aforesaid frames and adapted to be re-

ceived in said sockets to hold the aforesaid 10 head rests in position.

In witness whereof I have hereunto set my hand in the presence of two witnesses.

VICTOR LABELLE.
